Geo. Kimmel. ATTORNEY.

UNITED STATES PATENT OFFICE.

SAMUEL W. KENDRICK AND JOHN E. MARTIN, OF GREAT FALLS, MONTANA.

SHAVING BRUSH.

Application filed February 11, 1927. Serial No. 167,552.

This invention relates to shaving brushes, more particularly to that type of shaving brush having means for attaching a tube of shaving cream therewith and feed the 5 contents of the tube to the brush bristles for use, and has for its object to provide, in a manner as hereinafter set forth, a shaving brush of such class with means for separating and thinning out the bristles to permit 10 of the bristles to be readily cleaned when desired.

A further object of the invention is to provide, in a manner as hereinafter set forth, a shaving brush of the type referred to including a slide valve for controlling the discharge of the cream from the container therefor and furthermore so construct the brush whereby the discharge head of the container will be flush with the slide valve to 20 prevent the discharge of the cream when the brush element is removed for the purpose of cleaning the latter.

Further objects of the invention, are to provide, in a manner as hereinafter set forth, a shaving brush of the type referred to, which is simple in its construction and arrangement, strong, durable, compact, thoroughly efficient in its use, and comparatively inexpensive to manufacture.

With the foregoing and other objects in view, the invention consists of the novel construction, combination and arrangement of parts as hereinafter more specifically described and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a vertical sectional view of a shaving brush in accordance with this invention.

Figure 2 is a top plan view of the combined anchoring separating and thinning out element for the bristles of the brush.

Figures 3, 4 and 5 are top plan views of modified forms of combined, anchoring, separating and thinning out elements for the bristles.

Referring to the drawings in detail 1 denotes a tube or container of the compressible 55 type now generally employed for contain-

ing a shaving cream and the latter is discharged through the tubular head 2 of the tube 1 and such head 2 may be termed a nozzle. As is well known the head 2 is peripherally threaded and is normally closed 60 by a removable cap having threaded engagement with the peripheral threads of the head 2. The cap is not shown. The tube or container 1 is adapted to be mounted within the handle of the brush and with the tube in an inverted position and further with the closure cap for the head 2 removed. The length of the tube 1 is slightly less than the length of the chamber formed in the handle of the brush and which will be hereinafter referred 70 to.

A shaving brush of the type referred to, in accordance with this invention, comprises a handle section referred to generally by the reference character 3 and a brush section 75 referred to generally by the reference character 4. The handle section 3 consists of tubular member 5 of appropriate diameter and a combined coupling and socket forming member 6. The inner diameter of the member 5 is greater than inner diameter of a socket 7 formed in the inner end of the member 6. The outer end of the member 5 is enlarged as at 8 and has its inner end formed with internal threads 9. The periphery of the member 6 at the inner end thereof is formed with threads 10 engaged by the threads 9 whereby the members 5 and 6 are detachably connected together. The member 6 coacts with the socket 7 to provide a chamber 11 in which is mounted the container 1. The bottom of the socket 7 and which is indicated at 12 is of hopper like form. The inner end of the section 3 is closed by a hinged lid 13 which when 85 swung open permits of access being had to the container 1 so that the same can be compressed for the purpose of discharging cream therefrom through the head or nozzle 2. The breast 14 of the container 1 corresponds to the shape of the bottom 12 of the socket 7 and said breast 14 seats upon said bottom. The member 5 is constructed of any suitable material and this statement also applies to the member 6.

The member 6 includes an inner portion 15, an intermediate portion 16 and an outer portion 17. The socket 7 is formed in the inner portion 15 or member 6 and the outer portion 17 of said member is provided with 105 110

a socket 18. The rear inner end of the intermediate portion 16 forms the base of the socket 7 and the forward or outer end of the intermediate portion 16 forms the base 5 of a socket 18. The intermediate portion 16 centrally thereof is formed with a channel or passage 19 for establishing communication between the sockets 7 and 18 and the wall of said channel or passage 19 is 10 threaded as at 20. The head or nozzle 2 of the container 1 is extended into the channel or passage 19 and the peripheral threads of the head 2 are engaged with the threads 20 whereby the container 1 is detachably 15 connected to the intermediate portion 16 of the member 6. The diameter of the socket 7 is such as to snugly engage that portion of the container from which the breast 14 projects. The discharge of the cream through 20 the head or nozzle 2 is controlled by a slide valve 21 which extends across the edge of the head or nozzle 2, see Figure 1. The intermediate portion 16 of the member 6 is provided with a groove 24 for the slide valve 25 21 and the latter projects from the intermediate portion 16 and is bent at an angle to provide a finger piece 22. The length of that portion of the slide valve 21 which is mounted in the intermediate portion 16 is 30 of less length than the diameter of the socket 18. The slide valve 21 is arranged at the outer end of the channel or passage 19. The groove is indicated at 24. The wall of the socket 18 is provided with 35 threads 25.

The brush section 4 includes a set of bristles 25' and means for anchoring one end of said set together, as well as for separating and thinning the bristles of the 40 set.

With reference to Figures 1 and 2, the bristles 25' of the set, at one end thereof are embedded in a binder of rubber 26, in the form of an annulus and which is ar- 45 ranged between a threaded collar 28 and a combined bristle separating and thinning element 27 spaced from and connected at its inner end by a flat annulus 27' with the collar 28. The annulus 27' is integral with 50 such collar and element. The threads of the collar engage with the threads 25 whereby the brush section 4 is detachably connected to the member 6.

The element 27 consists of a hollow, 55 frusto-conical shaped body 29 open at each end and provided with spaced openings 30 for the reception of portions of the binder 26. The element 27 separates the bristles at their secured inner portions, as well as ad- 60 jacent thereto. The element 27 further binds the bristles together adjacent the inner ends thereof whereby said element 27, in connection with the collar 28, will anchor the secured inner portions of the bristles 65 thereto. The element 27 in connection with

the bristles provides a discharge passage for the cream, that is to say a passage for conducting the cream discharged from the container when the valve 21 is shifted to open position. The element 27 further provides 70 in connection with the bristles a part of said passage positioned outwardly with respect to the element 27, that is to say with respect to the larger end of the element 27. The passage formed by the element 27, in 75 connection with the bristles, tapers in an opposite direction. That part of the discharge passage positioned outwardly with respect to the element 27 is indicated at 31. When the set of bristles are removed together with the collar 23 and elements 27, or detached from the member 6, the element 27 permits of the bristles to be readily cleaned, as a cleaning fluid, such as water, 80 can be supplied to the bristles through the upper or reduced inner end of the element 85 27.

The element 27 as disclosed in Figures 1 and 2 is shown as provided throughout with 90 spaced circular openings 30, but with reference to Figure 3 the combined separating and thinning element for the bristles is indicated at 32 and the openings therein are substantially quadrangular in contour as at 95 33. The element 32 is of frusto-conical contour and gradually increasing in diameter from its inner towards its outer end.

With reference to Figure 4 the combined bristle separating and thinning element is 100 indicated at 34, is of frusto conoidal contour and formed with a series of radially disposed slots 35 into which the rubber binder extends.

The element 37 shown in Figure 5 is the same as that shown in Figure 4, with this 105 exception that the slots 36 thereof are of greater width than the slots 35.

The elements 32, 34 and 37 are frusto- 110 conical and open at each end.

The several forms illustrated of the combined separating and thinning element for the bristles are of conoidal contour and are surrounded by the binding material 26, such as rubber, for that end of the bristles 25' which are secured together. Each of said elements provides a passage for the flow of the cream from the head 2 of the container 1 into the space 31 formed between the bristles. Although reference has been made to rubber as a binder for the set of bristles at one end, yet it is to be understood that any suitable means can be employed for this purpose, but rubber is found preferable due to the fact that it is more adaptable as a binder than other materials. The combined bristle separating and thinning elements not only provide for the easy cleaning of the set of bristles 26 when detached from the member 6, but also thins the body of bristles around the shaving cream discharge, so that 115 120 125 130

the cream can readily flow the brush at the center thereof or rather into the space 31.

It is thought the many advantages of a shaving brush, in accordance with this invention can be readily understood, and although the preferred embodiment of the invention is as illustrated and described, yet it is to be understood that changes in the details of construction can be had which will fall within the scope of the invention as claimed.

What we claim is:—

1. In a shaving brush a combined bristle anchoring, separating and thinning element comprising a hollow annular structure formed with an open bottom and consisting of a top in the form of an annulus and outer and inner sides integral with the top and forming respective tubular walls, said top spacing said sides, and the tube formed by said inner side wall gradually decreasing in diameter from said open bottom to said top and with said outer side wall providing a chamber for receiving the inner end terminal portions of a set of bristles, said inner wall providing means for anchoring the bristles to said element adjacent the inner ends of the bristles and further forming axially of the set of bristles a shaving cream passage gradually increasing in diameter outwardly from said annulus.

2. In a shaving brush a combined bristle anchoring, separating and thinning element

comprising a flat annulus, a threaded collar 35 integral with and projecting axially from the outer edge of said annulus, and a hollow frusto-conical member having its smaller end integral with the inner edge of said annulus and projecting outwardly from the latter, said member opposing said collar and providing in connection therewith and with said annulus a chamber for receiving the inner ends of a set of bristles and further forming axially of the set of bristles a shaving cream passage gradually increasing in diameter outwardly.

3. In a shaving brush a combined bristle anchoring, separating and thinning element comprising a flat annulus, a threaded collar 50 integral with and projecting axially from the outer edge of said annulus, and a hollow frusto-conical member having its smaller end integral with the inner edge of said annulus and projecting outwardly from the latter, 55 said member opposing said collar and providing in connection therewith and with said annulus a chamber for receiving the inner ends of a set of bristles and further forming axially of the set of bristles a shaving cream 60 passage gradually increasing in diameter outwardly, said inner side provided with spaced cutout portions.

In testimony whereof we affix our signatures hereto.

SAMUEL W. KENDRICK.
JOHN E. MARTIN.
